UNITED STATES PATENT OFFICE.

GEORGE P. CRUMBAUGH, OF ST. LOUIS, MISSOURI, ASSIGNOR OF ONE-HALF TO EDWIN W. GROVE, OF ST. LOUIS, MISSOURI.

PLASTER-BOARD WITH REINFORCE-RIBS.

1,191,765.

Specification of Letters Patent. Patented July 18, 1916.

Application filed March 31, 1914. Serial No. 828,589.

To all whom it may concern:

Be it known that I, GEORGE P. CRUMBAUGH, a citizen of the United States, residing at St. Louis, in the State of Missouri, have invented new and useful Improvements 5 in Plaster-Boards with Reinforce-Ribs, of which the following is a specification.

This invention relates to plaster boards or wall coverings of that type embodying a 10 backing sheet to which a corrugated sheet is secured, and the primary object of the invention is to provide a plaster board or wall covering of this type with reinforcing means in engagement with and readily removable 15 from the corrugations, the purpose of the reinforcing means being to stiffen the plaster board or wall covering at points where it is desired to increase the resistance thereof relatively to weight strain imposed 20 thereon by the plaster covering and also to provide for strengthening the edge portions thereof that may be at the bottom or at other points of a wall demanding a more rigid structure as a covering than would be 25 provided by the board without the said reinforcing means. The improved plaster board or wall covering is adapted to be applied to the usual studding in place of the ordinary lath and plaster or to a continuous 30 partition surface or to a ceiling, and by the construction and arrangement of the several parts thereof the board is materially strengthened to resist and equalize weight strain that may be imposed thereon by the 35 plaster covering which is spread thereover.

The invention consists in the construction and arrangement of the several parts which will be more fully hereinafter described and claimed.

40 In the drawing: Figure 1 is a perspective view of a portion of a plaster board or wall covering embodying the features of the invention. Fig. 2 is a transverse vertical section through the plaster board or covering as shown by Fig. 1. Fig. 3 illustrates in transverse vertical section a modified form 45 of the board or covering and as particularly embodying a corrugated sheet or strip between the rear and front flat strips.

50 The numeral 5 designates a backing sheet which is flat and in the present instance preferably imperforate, and secured thereto by any suitable cement, such as asphalt or pitch, is a corrugated sheet or strip 6. The 55 sheets or strips 5 and 6 may be of any suit-

able material, but are preferably formed of paper, and it will be understood that the wall board or covering may be made in lengths and widths of various dimensions and is adapted to be rolled for convenience 60 in shipping and storage. It will be understood that the improved wall board or covering may have the sheets comprised in the organization of the same of any thickness, and the corrugations of the sheets 6 may 65 be varied as to their dimensions to adapt the same to different applications.

In the form of the improved device as shown by Figs. 1 and 2, reinforcing ribs or strips 7 are inserted longitudinally into the 70 corrugations of the sheet 6, the said reinforcing strips being readily removable and shiftable as may be desired to engage different corrugations. The purpose of shifting the ribs or strips 7 is to strengthen the 75 portions of the wall board or covering where the greatest reinforce may be desired, and this may be at the edges where the wall board or covering is secured at the bottom or top or at intermediate points as may be 80 found necessary, and the object of the reinforcing ribs is to give the wall board or covering greater rigidity or resistance to the weight strain of the plaster covering that may be applied thereover. It is obvious that 85 in applying the wall board or covering to studding or to wide gaps on suitable supports or even to flat surfaces the ribs or strips 7 will be materially advantageous and not only prevent cracking or sagging of the 90 plaster covering thereon, but will at the same time materially stiffen the board or covering and render the same more durable.

95 In Fig. 3 a backing sheet 5 and a corrugated sheet 6 are used as shown in Figs. 1 and 2, but in addition an outer flat facing sheet 8 is applied over the corrugations and the reinforcing ribs or strips 7 are removably inserted in the corrugations between 100 the backing and facing strips 5 and 8 at any point that may be desired, or if found necessary the ribs or strips 7 may be inserted between the corrugations and in some instances this particular arrangement of the ribs or 105 strips will be found advantageous. The improved wall board or covering as shown by Fig. 3 will be exceptionally convenient in forming partitions or in presenting flat surfaces, especially on side walls, and it is 110

possible to so ornament or arrange the facing strip 8 that the same may serve as the finishing covering or surface of the wall.

It is proposed to waterproof and fireproof 5 the wall board or covering as above explained in any manner desired, and the present construction is distinguished from that disclosed in my copending application, Serial Number 828,590 in that the corrugated sheet and backing sheet are without 10 perforations.

In applying the improved wall board or covering as herein disclosed to a wall or ceiling the same is laid flat against the studding or joists and secured, the edges of the 15 sheets being brought in close engagement to form a neat joint, and after the wall is covered the plaster coating, which will be of any suitable nature, is applied over the corrugated face of the covering or the corrugated surface exposed, which produces a key 20 means to hold the plaster covering in place and distribute the weight of the said plaster covering equally over the surface of the corrugated sheet or assembled sheets. It will 25 also be understood that any suitable securing means may be used to hold the sheets in place on the supports to which they are applied, and while studding and joists have 30 been mentioned as the supports against which the wall board or covering is placed, the said wall board or covering may be as efficiently secured over a flat surface or partition wall.

35 It is proposed to form the ribs or reinforcing strips 7 and 9 of wood, metal, compressed paper, or other suitable material and to have the same of such cross-sectional dimensions that they will snugly fit the corrugations or the spaces between the corrugations, and in the form where these ribs or 40 strips are disposed between the corrugations on the outer surface of the sheet 6 the outer edges of the ribs will lie flush with the outer

portions of the corrugations or will at least 45 not project beyond said corrugations, though in some instances they may be inwardly a distance from the corrugated surfaces.

What is claimed is:

1. A wall board or covering consisting of 50 a flat backing sheet, a front sheet firmly secured thereto and having corrugations extending in parallel relation and forming hollow inclosures which are clear throughout their length, the corrugations projecting 55 solely from one side of the backing sheet, and solid stiffening ribs longitudinally and loosely inserted endwise in the hollow corrugations and shiftable from one corrugation to another throughout the area of the wall 60 board or covering to increase and materially reinforce certain portions of the wall board or covering that may require greater strength or resistance, the ribs being held solely by frictional engagement with the 65 portions of the hollow corrugations and the flat backing sheet.

2. A wall board or covering of a flexible character having a flat backing sheet, a front sheet firmly secured to the backing 70 sheet and having corrugations extending in parallel relation and forming tubular inclosures relatively to the backing sheet, the inclosures being fully open throughout their entire length, and solid stiffening ribs longitudinally and loosely inserted in the tubular corrugations and shiftable from one corrugation to another, the ribs engaging the 75 backing sheet and the apexes and side portions of the corrugations and prevented 80 from turning in the corrugations.

In testimony whereof I have hereunto set my hand in presence of two subscribing witnesses.

GEORGE P. CRUMBAUGH.
